UNITED STATES PATENT OFFICE.

SAMUEL G. WILKES, OF WALLINGFORD, CONNECTICUT, ASSIGNOR TO R. WALLACE & SONS MFG. CO., OF WALLINGFORD, CONNECTICUT, A CORPORATION.

INSULATED HANDLE FOR VESSELS.

Application filed April 13, 1922. Serial No. 552,364.

To all whom it may concern:

Be it known that I, SAMUEL G. WILKES, a citizen of the United States, residing at Wallingford, in the county of New Haven and State of Connecticut, have invented a new and useful Improvement in Insulated Handles for Vessels; and I do hereby declare the following, when taken in connection with the accompanying drawings, and the characters of reference marked thereon, to be a full, clear, and exact description of the same, and which said drawings constitute part of this application, and represent in

Fig. 1 a side view of a portion of a handle vessel having one of my improved insulators applied thereto.

Fig. 2 a sectional view on the line 2—2 of Fig. 1.

Fig. 3 a sectional view on the line 3—3 of Fig. 1.

Fig. 4 a sectional view on the line 4—4 of Fig. 1.

Fig. 5 a sectional view, illustrating one method of manufacturing my device.

This invention relates to improvements in heat insulators for handle vessels, and particularly to insulators which are hollow and commonly known as "air insulators." The object of this invention is to produce an insulator of this type, which will have long bearings for the members of the handle, to which it is applied, and the invention consists in the construction as hereinafter described and particularly recited in the claim.

In carrying out my invention, I form the insulator in two parts,—one consisting of a cup 6 formed with an outwardly extending rim 7 and an upwardly extending flange 8, which is provided with a series of perforations 9. The other member consists of a cup 10 formed with a rim 11, which enters the flange 8 in the other member, to which it is

secured by soldering, brazing, or otherwise. The cups are reversed in position, so as to form two outwardly projecting members, 45 adapted respectively to be entered into the lower end of the handle 12 and the upper end of a lug 13, which are secured to a vessel 14 in the usual manner. As a convenient means for connecting the sections of the insulator, the cup 10 has its rim 11 formed with an annular shoulder 15, which permits the rim to set into the flange 8, and the edge of the rim rests upon the edge of the said flange. This permits the proper positioning 50 of the parts, and after they are brazed or soldered together, the shoulder 15 is removed, so as to provide a smooth surface, as shown in Fig. 4 of the drawings. These cups are of sufficient length to give a firm 60 seat for the ends of the handle 12 and lug 13, which are secured, by soldering or otherwise, and forms a large chamber through which 65 air may circulate to prevent the passage of heat from one member of the handle to the other.

While I have shown only one insulator installed in a handle, it is obvious that in some styles of handles, two insulators may be employed.

I claim:

A heat insulator for handle vessels, comprising a cup formed with an annular rim and an outwardly projecting flange, and a second cup formed with a rim connected 75 with the flange of the other cup, the said flange formed with a series of perforations.

In testimony whereof, I have signed this specification in the presence of two subscribing witnesses.

SAMUEL G. WILKES.
